UNITED STATES PATENT OFFICE

YOSHIO NAKAGAWA, OF BRODERICK, CALIFORNIA

ENGINE

Application filed October 28, 1929. Serial No. 403,099.

This invention relates broadly to engines, and has more particular reference to engines of the coil spring type.

A primary object of this invention is therefore to provide an improved coil spring engine comprising a plurality of coiled springs, a shaft driven from the springs, a power shaft, the invention further consisting in the provision of an engine of this type embodying a suitable transmission mechanism, means for controlling the speed of the engine together with an independently controlled motor for recoiling the springs.

A still further object of this invention is to provide a coil spring engine fully capable of doing such work as required by an engine and which is especially adaptable for use as a source of power for the locomotion of automobiles and similar vehicles.

A still further object of the invention is to provide an engine of the character above mentioned, which is comparatively simple in construction, and wherein the same embodies many advantages over known engines of this type and which will be found very useful for automobiles and similar vehicles in view of its simplicity, thus eliminating all the complicated and intricate parts of a gasoline engine now used for such purposes.

A still further object of the invention is to provide an engine of the above character, wherein its simplicity of construction insures less possibility of trouble and wherein the engine will be rugged, durable, eliminating all fine parts which may be in constant need of adjustment, or susceptible to breakage, and which will prove to be thoroughly safe in operation, free of such sources of danger as is attended internal combustion engines, and otherwise proving inexpensive, requires but little care and attention and wherein the same will be free from all other such troubles as are attended other known types of machinery and as a substitution of such known machinery an engine of this character will be found very advantageous.

Other objects and advantages of the invention will become apparent during a study of the following description taken in con-

nexion with the accompanying drawings, wherein:

Figure 1 is a longitudinal sectional view taken through the engine embodying the features of this invention.

Figure 2 is an end view thereof.

Figure 3 is a vertical transverse sectional view taken substantially on the line 3—3 of Figure 1.

Figure 4 is a horizontal sectional view taken substantially on the line 4—4 of Figure 1.

Figure 5 is a side elevation of the recoiling device, the same being shown applied to the engine.

Figure 6 is a perspective view of one of the slideable friction plates.

Figure 7 is a fragmentary detail view partly in section and partly in elevation showing the manner of coupling the recoiling mechanism to the engine.

With reference more in detail to the drawings, it will be seen that my engine includes an especially constricted casing designated generally by the reference character 5. The casing 5 embodies a platform 6 having end walls 7 and 8 rising therefrom. A horizontally disposed shaft 9 is rotatably supported on the end walls 7 and 8, the ends of which shaft 9 extend through and beyond the said end walls.

Mounted on that portion of the shaft 9 between the end walls 7 and 8, and adjacent said end walls are relatively large gear wheels 10—10. These gear wheels 10 are splined to the shaft 9 for rotation with said shaft. Between the gear wheels 10 and circumjacent the shaft 9 is a plurality of coil springs 11 disposed in end to end relation.

The inner ends of the coil springs 11 are secured to the central shaft 9 in any desired manner, and the outer ends of the coil springs 11 are secured to a shaft 12 as shown to advantage in Figure 2. These coil springs 11 fixed to the shafts 9 and 12 work in unison and provide the necessary power for the engine.

The gear wheels 10 and coil springs 11 operate as a unit through the medium of suitable connecting rods having nuts 13 on their

free ends and at the outer sides of the gear wheels. At one end, the shaft 9 is provided with suitable collars 14 on opposite sides of the wall 7 and at its other end with a collar 15 between the gear wheel 10 and the wall 8 to prevent endwise movement of said shaft 9.

That end of the shaft 9 extending into an end compartment 16 formed in one end of the casing 5 is equipped with a gear wheel 17. This end compartment 16 may be termed the transmission compartment and therein is located the transmission gearing designated generally by the reference character T. Within the compartment 16 is an intermediate shaft 18, one end of which shaft is journaled in the lower end portion of the wall 8 and the other end of the shaft journaled in a bearing 19 formed on the end wall 5' of the housing 5.

The shaft 18 is equipped with a pinion 20 with which the gear wheel 17 is in mesh for imparting rotation to said shaft 18. The shaft 18 also has rotatably mounted thereon three relatively large gear wheels 21. These gear wheels 21 are in mesh with pinions 22 on a power shaft 23. There are three of such pinions 22, one for each of the gear wheels 21. This power shaft 23 has one end journaled in the forward end of the platform 6 as at 24 and its other end in a bearing 25 on the end wall 5'.

At said other end the power shaft 23 extends through the wall 5' and to this power shaft 23 the load to be driven therefrom may be operatively attached in any suitable manner.

Further, it will be seen that the transmission mechanism T also embodies a pair of pinions 26 on the shaft 18 between the gear wheels 21 and these pinions 26 are in mesh with large gear wheels 27 on the shaft 23. Manifestly, rotation of the shaft 23 is caused through the intermeshing of these gears and pinions.

As a suitable brace for the shafts 18 and 23, there is provided a double bearing bracket 28 in the compartment 16 and embodying a lower bearing 29 for the shaft 23 and an upper bearing 30 for the shaft 18.

The invention further comprehends the provision of a suitable speed control for the engine. As shown to advantage in Figures 1 to 4 inclusive, this mechanism comprises an elongated housing H, which housing H is located in the bottom of the casing 5 beneath the forward end of the platform 6. Extending longitudinally through the housing H and rotatably supported in the end walls of the housing is a shaft 31.

The shaft 31 extends through the forward end wall of the housing H, and the extended end of the shaft is equipped with a pinion 32 with which one of the large gear wheels 27 on the shaft 23 is in mesh. Mounted on the

shaft 31 within the housing H is a plurality of spaced apart friction plates 33 adapted to rotate with the shaft 31. Also mounted on the shaft 31 within said housing and between the rotative plates 33 are friction plates 34.

These plates 34 are adapted for sliding movement longitudinally of the shaft 31 but are held against rotation during relative movement of the shaft 31, the upper and lower edges of the plates 34 being operable in longitudinally extending grooves 35 and 36 respectively, the groove 35 being formed in the underface of the platform 6 and the groove 36 being formed in the bottom of the housing H as shown to advantage in Figure 3.

The alternately arranged plates 33 and 34 are disposed on the shaft 31 between the forward end wall of the housing H and a control disc 35', which control disc 35' has an annularly grooved hub 36' slidable on the shaft 31. A coil spring 37 is convoluted about the shaft 31 and has one end thereof impinging against the rear or opposite end wall of the housing H, and the other end of said spring 37 impinges against the hub 36' of the control disc 35'.

This housing H is in the nature of a casting and has formed integrally therewith at the forward end thereof a lateral cylinder 38. Mounted for reciprocatory movement within the cylinder 38 is a piston 39, the piston rod 40 extending through the closure end plate 41 which is threaded in the open end of the cylinder 38 for normally closing said cylinder. A fork member 42 has the free end of its shank rigidly secured to the outer free end of the piston rod 40 as at 43. The shank of the fork 42 is operable in a suitable slot 44 formed in the side wall of the housing H and the legs 45 of the fork member straddle the hub 36 of the control disc 35, said legs fitting in the groove of the hub 36 as shown to advantage in Figure 1.

To one side of the cylinder 38 the casting designated generally by the reference character C which embodies the housing H and the piston 38 is also formed to provide a fluid compartment 46, with which compartment 46 the cylinder 38 is in communication through the medium of a duct or passage 47. As intimated, the compartment 46 is adapted to be filled with fluid, and mounted for reciprocatory movement within this compartment is a plunger 48.

Any kind of means may be utilized for reciprocating the plunger 48. Manifestly, when a pressure from any suitable source is applied to the plunger 48 for exerting a push upon the plunger, the fluid within the compartment 46 will be forced through the passage 47 and into the cylinder 38. Thus the fluid will exert a pressure on the piston 39 for moving the rod 40 outwardly of the cylinder.

Through the medium of the fork member

42 engaging the hub 36' of the control disc 35'; said disc 35' will be moved on the shaft 31 against the action of the spring 37, whereupon the friction plates 33 will be moved out of frictional engagement with the relatively stationary friction plates 34 and the shaft 31 then is free to rotate, whereupon the power or drive shaft 23 is set in motion through the medium of the transmission gearing T upon the expansion or uncoiling of the springs 11. When a pull is exerted on the plunger 48, pressure in the cylinder 38 is decreased and the spring 37 will expand for sliding the control disc 35' to its former position for setting up friction between the plates 33 and 34, thus resulting in a braking action on the shaft 31 and consequently reducing the speed of the drive shaft 23 or bringing the shaft to a complete stop as may be regulated by the pressure in the cylinder 38 the pressure being controlled by the position of the plunger 48 within the chamber or compartment 46.

A horizontally disposed shaft 51 has its ends journaled in and extending through the walls 7 and 8 at the upper ends of said walls. This shaft 51 extends to one side of the springs 11, said shaft 51 being equipped with pinions 52—52 in mesh with the gear wheels 10. Adjacent its ends, said shaft 51 is also equipped with ratchet wheels 53—53. Dogs 54 are pivotally mounted on the upper ends of said walls 7 and 8, the free ends of said dogs engaging with the teeth of the ratchet wheels 54 to prevent rotation of the shaft 51 in one direction.

At one end the shaft 51 has a sprocket 53 mounted thereon and the adjacent end of the central shaft 9 has a sprocket 55 mounted thereon. A sprocket chain 56 is trained over the sprockets 54 and 55 thus affording an operative connection between said shafts 9 and 51. At this said end, the shaft 9 extends through the upper end of an angular bracket 57 mounted on the end wall 7. At this end, the shaft 9 is also provided with an annular series of ribs 58.

The purpose of the ribs 58 will be herein-after more fully set forth. The recoil mechanism for the spring motor comprises a pedestal 59 mounted on rollers 60, and an electric motor 61 is mounted on the top of the portable pedestal 59. A short shaft 62 is keyed as at 63 to the armature shaft 64 of the motor 61. This shaft 62 is provided with an annular series of ribs 65. A hollow connecting shaft or sleeve 66 has a series of annular internal grooves 67 formed therein.

This shaft 66 telescopically receives the shaft 62, the ribs 65 of which are receivable in the grooves 67 for keying said connecting shaft 66 to said shaft 62. At its opposite end, the shaft 66 is adapted to telescopically receive the ribbed end of the shaft 9, the ribs 58 of said shaft 9 being receivable in the grooves 67. Thus the shaft 66 provides an

adjustable connection between the shaft 62 and shaft 9.

The motor 61 is of course controlled from a suitable switch not shown, and when the switch is closed for operating the motor, the coils 11 will be tightly wound or compressed for storing up energy, the coils being rewound from said motor through the medium of the shafts 62, 66, and 9, which latter shaft 9 has the chain and sprocket connection as before mentioned with the shaft 51, the pinions 52 carried by said shaft 51 meshing with the gear wheels 10.

The dogs 54 engaging with the teeth of the ratchet wheels 53 carried by said shaft 51 will, as is obvious, prevent the gears 10 from turning in the opposite direction, the dogs 54 thus acting as safety catches to prevent casual unwinding or expansion of the coil springs 11.

After the coils 11 have been fully wound, the connecting shaft 66 may be disengaged from the shaft 9 and then by moving plates 33 and 34 out of frictional engagement with one another in a manner hereinbefore set forth in detail, the engine is set in operation, the speed of the spring motor or engine, and the starting and stopping thereof, being controlled as has also been hereinbefore clearly set forth.

It is believed that from the foregoing description taken in connection with the accompanying drawings, a clear understanding of the operation, construction, utility and advantages of a coiled spring motor of this character will be had by those skilled in this art without a more detailed description.

Even though I have herein shown and described the preferred embodiment of my invention, it is to be understood that the same is susceptible to such changes fully comprehended by the spirit of the invention as herein described, and the scope of the appended claims.

Having thus described the invention, what is claimed is:

1. In an engine of the class described, a rotatably mounted shaft, a pair of spaced apart gears mounted on said shaft, a plurality of coiled springs circumjacent the shaft between said gear wheels, said springs being arranged in end to end relation, means operatively connecting said springs to each other and said gear wheels, a horizontal shaft, means for rotatably mounting said horizontal shaft, pinions on said horizontal shaft in mesh with said gear wheels, a chain and sprocket connection between said shafts, a power shaft, transmission gearing for transmitting the movement of the first-mentioned shaft to said power shaft, and fluid pressure control means for controlling the speed of said engine.

2. In an engine of the class described, a rotatably mounted shaft, a pair of spaced apart gears mounted on said shaft, a plurality of coiled springs circumjacent the shaft be-

tween said gear wheels, said springs being arranged in end to end relation, means operatively connecting said springs to each other and said gear wheels, a horizontal shaft, 5 means for rotatably mounting said horizontal shaft, pinions on the said horizontal shaft in mesh with said gear wheels, a chain and sprocket connection between said shafts, a power shaft, transmission gearing for transmitting 10 the movement of the first-mentioned shaft to said power shaft, fluid pressure control means for controlling the speed of said engine, a prime mover, and including a drive shaft, and means for coupling said drive shaft 15 to the first-mentioned shaft for recoiling said springs.

3. An engine of the class described, a rotatably mounted shaft, a pair of spaced apart gear wheels on said shaft, a plurality of coil 20 springs adjacent said shafts and arranged in end to end relation between said gear wheels, means operatively connecting said springs one with the other, and with said gear wheels, a horizontal shaft, means for rotatably mounting 25 said horizontal shaft, pinions on the horizontal shaft in mesh with said gear wheel, chain and sprocket means operatively connecting said shafts, a prime mover including a shaft, and means operatively connecting the 30 shaft of the prime mover with the first mentioned shaft for recoiling said springs.

4. An engine of the class described, a rotatably mounted shaft, a pair of spaced apart gear wheels on said shaft, a plurality of coil 35 springs adjacent said shafts and arranged in end to end relation between said gear wheels, means operatively connecting said springs one with the other, and with said gear wheels, a horizontal shaft, means for rotatably mounting 40 said horizontal shaft, pinions on the horizontal shaft in mesh with said gear wheel, chain and sprocket means operatively connecting said shafts, a prime mover including a shaft, means operatively connecting the 45 shaft of the prime mover with the first mentioned shaft for recoiling said springs, a power shaft, means for transmitting movement of said first shaft to said power shaft, friction clutch means operatively associated with 50 the power shaft for controlling the speed of said power shaft.

5. An engine of the class described, a rotatably mounted shaft, a pair of spaced apart gear wheels on said shaft, a plurality of coil 55 springs adjacent said shafts and arranged in end to end relation between said gear wheels, means operatively connecting said springs one with the other, and with said gear wheels, a horizontal shaft, means for rotatably mounting 60 said horizontal shaft, pinions on the horizontal shaft in mesh with said gear wheel, chain and sprocket means operatively connecting said shafts, a prime mover including a shaft, means operatively connecting the 65 shaft of the prime mover with the first-men-

tioned shaft for recoiling said springs, a power shaft, means for transmitting movement of said first shaft to said power shaft, friction clutch means operatively associated with the power shaft for controlling the speed 70 of said power shaft, and fluid pressure means controlling said clutch means.

6. In an engine of the class described, a spring motor including a shaft driven thereby, a prime mover, means for transmitting power from said prime mover to said spring motor for recoiling the springs of said motor, a spring actuated hydraulic controlled friction disc brake for controlling the speed of 75 said spring motor, and including a rotatable shaft, a power shaft adapted to be driven by said spring motor, and transmission gearing connecting the shaft of said spring motor with said power shaft and with the shaft of said brake.

7. An engine of the character described comprising in combination a spring motor including a shaft driven thereby, a prime mover, means for coupling the shaft of the prime mover to the first mentioned shaft for 80 recoiling the springs of said spring motor, a multiple friction disc hydraulic controlled brake including a shaft, and transmission gearing operatively connecting the shaft of said spring motor with the shaft of said 85 brake.

In testimony whereof I affix my signature.
YOSHIO NAKAGAWA.
